UNITED STATES PATENT OFFICE.

JOHN L. G. LEHMAN, OF KANSAS CITY, MISSOURI.

FOLDABLE CUFF.

1,168,945.

Specification of Letters Patent. Patented Jan. 18, 1916.

Application filed May 20, 1915. Serial No. 29,357.

To all whom it may concern:

Be it known that I, JOHN L. G. LEHMAN, a citizen of the United States, residing at Kansas City, in the county of Jackson and State of Missouri, have invented certain new and useful Improvements in Foldable Cuffs, of which the following is a specification, reference being had therein to the accompanying drawing.

This invention relates to improvements in shirts or shirt waists, and although, as will appear to workers in the art, the same is capable of embodiment in fabrics of various kinds, will be primarily found useful in connection with soft or semi-soft materials.

It is a common experience that the cuffs being the more exposed portion of a shirt, become soiled within an unreasonably short period of time, and where the cuffs are attached and not reversible, the shirt must be discarded while the body is comparatively clean, resulting in undue wear and tear of the garment from unnecessarily repeated laundrying processes. Again, it is known that the exposed outer edge of a cuff whether of the single or folded style, will wear and become frayed or impaired before other portions of the garment. To overcome the disadvantageous characteristics of a shirt to which I have above alluded, many attempts have heretofore been made to enable the detachment of the cuff from the shirt sleeve, and as a more modern step in advance, permanently attached cuffs capable of being reversed, or folded in opposite directions, have been devised. It is to the latter type of cuff that my present invention particularly relates.

In the prevailing use of a foldable cuff, it is the practice, in order to present as neat as possible appearance, to have the cuff folded upon itself so that the outer fold is in the nature of a free layer or flap held in position merely by the coupling function of the usual cuff buttons or links. In case of soiling or objectionable wearing of the folded edge of the cuff, the unsightly effect of the same may be overcome by folding the free layer or flap of the cuff inwardly to immediately surround the wrist of the user, but in doing this the desired refined appearance of the adjoining sleeve and cuff is marred, unless special provision is made to imitate the appearance of the first mentioned normal folding of the cuff with the free flap or layer outermost. I accomplish this effect in an

improved manner, through the medium of the details in arrangement and construction of parts set forth in the specific description hereinafter contained, and the same will be readily appreciated from a reading of the same in connection with the accompanying drawings forming part hereof and in which the preferred embodiment of the invention is illustrated.

In the said drawings, Figure 1 is a perspective view of a cuff in its original or normally folded condition, Fig. 2 is a similar view with the cuff folded inwardly to conceal the normal fold or edge of Fig. 1, and to present a fresh edge to the cuff, Fig. 3 is a sectional view through the cuff of Fig. 1, and Fig. 4 is a sectional view through the cuff of Fig. 2.

Referring more specifically to the drawings, —A, represents the usual shirt sleeve, this as well as the cuff being conveniently though not essentially formed of a soft material, for example, silk, and B designates, in a general way, the improved cuff, the latter being shown in disproportionate and exaggerated manner to more clearly illustrate the subject matter.

I preferably form the cuff of a single piece of material folded upon itself to present (assuming the cuff to be extended) an outer ply C and an inner ply D. The outer ply just mentioned is folded upon itself around the upper edge thereof for a substantial distance as represented at E, the lower edge of the fold E being stitched as at F to the edge of the sleeve A, the inner ply D being similarly folded, in an opposite direction but for a slight extent only as at G, merely to overcome the exposure of a raw edge of fabric, this last mentioned folded portion being also stitched to the lower edge of the sleeve by a line of stitching H.

Adjoining the outer ply C and introduced into the folded upper edge of the same is a reinforcing or stiffening ply J, of linen or other suitable material, the same being stitched to and between the outer and inner plies C and D by a marginal finishing line of stitches K extending around the cuff, and including the folded upper edge of the outer ply C, within and to the members of which folded upper portion the stiffening or reinforcing ply J is also secured by said stitching, as shown.

From the foregoing construction, it will

be appreciated that the cuff being formed of a single piece of material, presents a neat rounded edge when the cuff is folded along the center line indicated at L, with the free flap or layer M outermost, and when the free flap or layer is turned inside, or reversely folded, the rounded upper edge of the free extension constituted by the folded portion C—C will present a similar rounded edge; and also, by reason of the considerable depth and freedom of the folded upper edge of the ply C, the same will present the same appearance as the normal appearance of the cuff with the free layer or flap outermost. In the reversed position of the cuff, the finishing line of stitching K only is exposed, while the securing line of stitches F and H are located at a position to be constantly concealed and to permit the free upper folded portion C—C to play back and forth relative to the sleeve without suggesting in any way that the cuff has been reversed, a consideration which is always desirable, particularly through the heated seasons where it is customary to remove the coat of the wearer.

I am aware that it has heretofore been suggested that the folded upper edge of the outer ply of the cuff might be secured to the shirt sleeve, for instance, by passing the line of stitching K through the folded edge and through the material of the sleeve, but the result is merely a rounded edge appearance, and presents no free flap of any substantial length in simulation of the normal free outer layer or fold of the cuff. As distinguished from this, my special construction enables the securing of the cuff to the sleeve at a point any distance desired below the folded upper edge of the outer ply in a hidden position with reference thereto, leaving it optional whether or not the line of finishing stitches K be employed.

It will be appreciated that it is also optional whether the stiffening or reinforcing linen J be introduced within the folded cuff proper constituted by the continuous plies C, D.

While I have herein disclosed a specific embodiment of my invention, it will be clear that changes or alterations may be made therein without departing from the spirit of the invention and as may be included in the hereto appended claim.

I claim—

In combination with a shirt sleeve, a reversible foldable cuff therefor having an outer ply formed to constitute a folded upper portion free with reference to the sleeve, marginal stitching to retain the edge of the folded portion in flat condition, said stitching passing through the said folded portion only of the cuff, and not through the sleeve, the inner layer of said folded portion extending downwardly a substantial distance below the stitched marginal edge thereof, and stitching securing the lower edge of said inner layer to the adjacent lower end portion of the sleeve independently of the outer layer of the folded portion, so that said folded portion is loosely related to the sleeve to a substantial depth extending below the stitched marginal edge of the folded portion, the central portion of the body of the cuff being free relative to the sleeve to permit folding of said body upon itself in either direction to present a rounded exposed or wearing edge projected below the sleeve, substantially as described.

In testimony whereof I hereunto affix my signature in the presence of two witnesses.

JOHN L. G. LEHMAN.
